EX

UNITED STATES PATENT OFFICE.

CHRISTIAN P. ROOS, OF NEW YORK, N. Y., ASSIGNOR TO THE ROBERT GRAVES COMPANY, OF SAME PLACE.

DESIGN FOR WALL-PAPER.

SPECIFICATION forming part of Design No. 20,457, dated January 6, 1891.

Application filed November 25, 1890. Serial No. 372,641. Term of patent 3½ years.

To all whom it may concern:

Be it known that I, CHRISTIAN P. ROOS, a citizen of the United States, residing at New York, in the county and State of New York, 5 have invented and produced a new and original Design for Wall-Paper, of which the following is a specification, reference being had to the accompanying drawing, forming part thereof, and representing a piece of wall-paper bearing said design.

The leading features of the design consist of the substantially circular figures A, arranged equidistant from each other, the ornamental scrolls B within the figures A, and the ornamental scrolls C between said figures, all 15 substantially as shown in the accompanying drawing.

I claim—

The design for wall-paper, substantially as shown and described. 20

Signed at the city of New York, in the county and State of New York, this 24th day of November, 1890.

CHRISTIAN P. ROOS.
